UNITED STATES PATENT OFFICE.

GEORGE H. MEISER, OF CHICAGO, ILLINOIS, ASSIGNOR TO BLACK HAWK MOTOR CO., OF ROCK ISLAND, ILLINOIS, A CORPORATION OF ILLINOIS.

DESIGN FOR A MOTOR-CYCLE FRAME.

43,625.

Specification for Design.

Patented Feb. 25, 1913.

Application filed September 24, 1912. Serial No. 722,126. Term of patent 7 years.

To all whom it may concern:

Be it known that I, GEORGE H. MEISER, a citizen of the United States, residing at Chicago, in the county of Cook and State of Illinois, have invented a new, original, and ornamental Design for a Motor-Cycle Frame, of which the following is a specification, reference being had to the accompanying drawing, forming a part thereof.

My new motor cycle frame of improved design has the upper horizontal bar of rectangular form, sufficiently large to serve as a fuel and oil reservoir, its ends being tapered inward and formed integral with the heads

secured on the seat-carrying post and front fork post.

The design is illustrated in the accompanying drawing in which—

Figure 1 is a side elevation. Fig. 2 is a transverse section on the line 2—2 of Fig. 1.

What I claim is:

The ornamental design for a motor cycle frame as shown, and described.

GEORGE H. MEISER.
